UNITED STATES PATENT OFFICE.

CRIS. W. WIEGAND, OF LOS ANGELES, CALIFORNIA.

STRUCTURAL FASTENER.

1,229,365.

Specification of Letters Patent. Patented June 12, 1917.

Application filed July 21, 1913. Serial No. 780,097.

To all whom it may concern:

Be it known that I, CRIS. W. WIEGAND, a citizen of the United States, residing at Los Angeles, in the county of Los Angeles and State of California, have invented certain new and useful Improvements in Structural Fasteners, of which the following is a specification.

This invention relates to improvements in structure forming devices and has particular relation to means for facilitating the formation of concrete structures, buildings or the like. It is an object of the invention to provide means whereby structural forming pieces may be anchored and held in proper position with relation to concrete forming the structure.

It is also an object of the invention to provide form holders and spacing devices of hollow pieces compressed at certain points to afford holding projections within the same, the said pieces being thus adapted to receive lag screws or other similar means for anchoring and holding forming boards or other devices with respect to the concrete.

With these and other objects in view the invention comprises certain novel constructions, combinations and arrangements of parts as will be hereinafter fully described and claimed.

In the accompanying drawing forming a part of this specification:

Figure 1 is a vertical sectional view through portions of the wall, ceilings or floors of a cement concrete building, forming boards being shown secured in position on the parts of the same.

Fig. 2 is a sectional view through a portion of the forming boards and timbers, and an adjacent wall, spacing and anchoring means for the formation of the floor or ceiling of the structure being shown in side elevation.

Fig. 3 is a detail view of a structural fastener partially in side elevation and partially in section illustrating the manner of forming threads therein upon a mandrel.

Fig. 4 is a detail perspective view of an anchoring means for a ceiling or floor and for holding shaping boards and afterward other fixtures thereto.

The present invention is designed to afford means to facilitate the proper formation of the successive portions of a cement

concrete structure and to properly hold the forming boards and pieces in position for this purpose. The invention is especially designed also to provide a fastener for supporting and holding the forming boards and pieces in position, said fastener being also adapted to afford means for securing fixtures, piping and other articles to the wall and ceiling of such concrete structure.

The details and features of the invention will now be specifically described reference being had to the drawing in which 1 indicates a structural fastener adapted to act also as a spacing member and 2 a shorter form of fastener which is not designed to extend all the way through walls, ceilings or floor.

In forming the vertical walls of a cement building or like structure, it is necessary to provide holding and shaping means for receiving the concrete cement when in plastic or semi-liquid form, so as to hold the same until it is set or hardened in proper shape. The forms frequently employed may be made of boards 3 secured to bars 4 which are arranged to extend transversely of the boards. Such forms are set up to shape the inner and outer surfaces of the concrete structure and while they should be bound together, they should also be properly spaced with respect to each other. For this purpose structural fasteners 1 are interposed between the boards 3 of the inner and outer forms. Timbers 5 are laid against the outer edges of the bars 4 and bolts 6 are passed through said timbers 5, their inner ends being screw threaded and adapted to engage interiorly arranged threads in said structural fasteners 1 as clearly shown in Fig. 1 of the drawing.

Washers 7 are preferably interposed between the ends of said structural fasteners and the boards 3 to prevent said ends from becoming embedded in the surface of the boards.

The formation of the said structural fasteners 1 forms an important feature of the invention. While the fastener may be of any hollow or tubular material having screw threads in its ends, it is preferably made of piping of suitable diameter which is placed between dies to crimp the same upon a suitable former or mandrel 8. It is usually sufficient to crimp or force inwardly the end portions of said pipe or tubes for

this purpose. The dies, not shown, may be of any usual type but are provided with inner surfaces adapted to form, when brought together, a spiral shaped impression 9 upon 5 the outer surface of the pipe forming the fastener 1 as clearly shown in Fig. 3. By inserting a mandrel 8 in the end of the pipe before the dies are brought together thereon, the impression made by the dies will 10 swage the metal inwardly between the threads of the mandrel as clearly shown in Fig. 3 and thus form interior threads 10 adapted to receive the screw threaded ends 15 of the securing bolts 6. If the threads formed are not sufficiently pronounced, a cutter having thread forming cutting edges may be turned in the ends of the fastener before using the same. The crimping of the ends of the pipe just described also reduces 20 the diameter of the pipe exteriorly to some extent as shown in Fig. 3 and the hold of the cement concrete upon said pipe after it has been flowed about it and allowed to set 25 is correspondingly strong.

25 This manner of producing fasteners is also of importance in that it is commercially cheap and further produces fasteners which are more effective than if the inner surface of the pipe or tubes were only threaded in 30 the usual way. The fasteners are left embedded in the cement concrete of the wall or other portion of the structure and afford means for attaching any desired materials or fixtures to said wall where desired. Where it is not wished to use the 35 same for this purpose, the spaces occupied by the washers are smoothed over with cement, thus covering the ends of the tubular fastening as indicated in Fig. 1 of the drawing. The forms are of course 40 removed when the wall structure has become sufficiently hard and the said forms are set up again to provide for the formation and construction of upper portions of 45 the wall structure of the building. Where floors or ceilings are formed, the form just below the ceiling upon the inner surface of the vertical wall is held in position by a beam 11, bolted to some of the structural 50 fasteners 1 and ceiling supporting beams. 12 are located with their ends resting thereon and on the ends of the upright bars 4. These beams may be connected by angle plates 13 as shown in Figs. 1 and 2. Surface 55 boards 14 and 15 are then placed upon the beams 12 to receive the concrete of the ceiling and the floor, said boards being either set loosely in place or fastened in any desired manner to the said beams 12. To facilitate 60 a proper and smooth formation of the upper surface of said ceiling or floor a further form securing beam, as 16, is applied in the upper angle formed between the vertical wall and the floor. This beam may 65 be secured to spacing structure fasteners 1

arranged both in the vertical wall and in the ceiling as illustrated in Fig. 1. The beam 16 forms a guide for the drawing of a smoothing board over the upper surface of the ceiling or floor concrete, said smoothing board having a proper notch in its end to fit upon the beam 16 and yet reach and move flush with the bottom of said beam. It is preferable to carry a portion of the vertical wall at least to the height of the 70 top of the beam 16 to properly receive and position forms for the wall that is to be built above.

In the ceiling or floor it is usually desired to place reinforcements in a more or less 80 central position between the surfaces of the concrete. For this purpose the structural fasteners may be made approximately in half lengths as shown in Fig. 4. In this instance one end is crimped and screw threaded 85 as at 17, while the other end is split and the prongs thus formed are turned outwardly to provide anchoring means and reinforcement holding projections. Thus two oppositely arranged prongs 18 may be arranged at such an angle as to support the reinforcement bar 19 between them, and two 90 prongs as 20 may be bent out of the way of said bar this forming more effective anchoring means for the fastener. After the 95 boards 15 for the ceiling have been set in place, as many fasteners 2 may be put into position as desired and the reinforcing bars of any preferred shape may be rested thereon, whereby they will be held above the 100 boards 15 so as to be properly embedded in the cement concrete of said ceiling or floor as clearly indicated in the drawing. In many structures also it is desired to suspend piping or other fixtures from the ceiling. For this purpose the anchoring pieces 1 and 2 located in the ceiling may be engaged by eye bolts 21 to which such fixtures 105 may be attached. The proper arrangement of the fasteners 2 for the supporting of the 110 pipes of overhead fire sprinkling systems as in large buildings or stores, affords a ready anchoring means for the piping thereof as illustrated in Fig. 1. Hangers 22 inclosing the pipes can readily be hooked upon the 115 eye bolts 21. It will be evident of course that any articles or fixtures can be secured to said embedded fastener without departing from the spirit of the invention. The crimped ends of the fasteners 2 are preferably formed in the same manner as the ends 120 of the fasteners 1 above described.

It will also be evident from the above 125 description that the structural fastening means may be adapted to the arrangement of spacing boards or materials used in all kinds of cement structure and for various kinds of buildings. The fasteners are cheaply made and may therefore be left embedded in the cement for strengthening the 13

structure as well as affording holding means for anything that is to be fastened to walls or ceilings.

The use of the angle plates 13 greatly facilitate the securing of the beams 11 and 12 together and by applying them in the angles of their meeting edges as shown in Figs. 1 and 2 of the drawing, a single bolt may be used for securing each of the flanges 10 of the said plates to the said beams. The plates, however, are provided with two apertures at each end so that they may be set upon either side of the beams at their meeting points and either hole at either end 15 thereof may have the securing bolts pass through it. The plates are thus capable of use interchangeably as rights or lefts. The manner of securing the bolts, one in each flange of the angle plates 13 makes it impossible for the parts to get out of position even though one bolt only be used at each 20 end of the plates.

What is claimed is:

1. A structural fastener comprising a tubular spacing member having a crimped end portion whereby holding means is provided interiorly in said fastener.
2. A structural fastener comprising a tubular spacing member having its end portions crimped and formed with spiral indentations whereby securing screw threads are formed upon the inner surface thereof, said threads being adapted to receive and hold screw threaded bolts.
3. A structural fastener and spacing member having its walls contracted and bent to

form interior threads and formed with outwardly end flaring portions constituting anchoring means, said fastener forming spacing means for the structure and co-operating bolts adapted to screw into the ends of said member for fastening articles to said fastener.

4. The combination with forming boards, beams and securing bolts, of a tubular structural fastening device adapted to space said forms from each other, and having reduced crimped end portions formed with securing threads in the same for receiving the ends of said bolts, and washers interposed between the forms and the ends of said fasteners.

5. A structural forming apparatus comprising the combination with forming boards and holding beams, of structural spacing members adapted to positively space and hold the said boards and beams preparatory to the forming of a concrete structure, and having reduced screw threaded end portions forming abutment ends, beam 60 holding plates, and tap bolts adapted to screw into either or both ends of said spacing members, whereby forming boards, beams and plates may be held against the ends of said spacing members according as 65 each or all may be used.

In testimony whereof, I have hereunto set my hand, in presence of two witnesses.

CRIS. W. WIEGAND.
